(57) **CLAIM**

The ornamental design for a magnetic wire puller, as shown and described.

DESCRIPTION

FIG. 1 is a left side view of a magnetic wire puller according to this disclosure, showing a handle in a first position;

FIG. 2 is a right side view of the magnetic wire puller of FIG. 1;

FIG. 3 is a front view of the magnetic wire puller of FIGS. 1 and 2;

FIG. 4 is a back view of the magnetic wire puller of FIGS. 1-3;

FIG. 5 is a top view of the magnetic wire puller of FIGS. 1-4;

FIG. 6 is a bottom view of the magnetic wire puller of FIGS. 1-5;

FIG. 7 is a left side view of the magnetic wire puller of FIGS. 1-6, showing the handle is a second position that is different from the first position;

FIG. 8 is a perspective view from the front, above, and right of the magnetic wire puller of FIGS. 1-7, showing the handle in a third position that is different from the first and second positions; and,

FIG. 9 is a perspective view from the back, below, and right of the magnetic wire puller of FIGS. 1-8, showing the handle in the third position.

The broken lines shown are included for the purpose of illustrating portions of the magnetic wire puller that form no part of the claim. The shading lines in the drawings show contour and are not intended to indicate surface orientation.
